UNITED STATES PATENT OFFICE.

BERNARD F. MACY, OF ROSLINDALE, MASSACHUSETTS.

DESIGN FOR AN EGG-SEPARATOR.

SPECIFICATION forming part of Design No. 28,876, dated June 14, 1898.

Application filed September 20, 1897. Serial No. 652,382. Term of patent 7 years.

To all whom it may concern:

Be it known that I, BERNARD F. MACY, of Roslindale, in the county of Suffolk and State of Massachusetts, have invented a certain new and original Design for Egg-Separators, of which the following is a description sufficiently full, clear, and exact to enable those skilled in the art to which it appertains or with which it is most nearly connected to make and use the same.

Figure 1 of the drawings is a plan view of an egg-separator embodying my design. Fig. 2 is a view of the same in elevation.

The leading or material feature of my design for an egg-separator consists of the unitary article made the subject of the accompanying illustration.

As shown, my design comprises the nearly semispherical bowl-shaped body *a*, terminating at its upper edge in an outwardly-project-

ing substantially horizontal rim or flange *b*. At the bottom of the body *a* is a base *c*, the bottom of which is horizontal and the sides of which are slightly tapering. The body *a* is formed with a horizontal slot *d* in one side 25 near the base, said slot being rounded at the ends, as shown.

Having thus described my invention, what I claim is—

The design for an egg-separator substantially as herein shown and described. 30

In testimony whereof I have signed my name to this specification, in the presence of two subscribing witnesses, this 15th day of September, A. D. 1897.

BERNARD F. MACY.
